UNITED STATES PATENT OFFICE.

JAMES MAIR, OF PHILADELPHIA, PENNSYLVANIA, ASSIGNOR TO HEMPHILL COMPANY, OF CENTRAL FALLS, RHODE ISLAND, A CORPORATION OF MASSACHUSETTS.

YARN-PLAITING-TENSIONING MEANS FOR KNITTING MACHINES.

Application filed January 13, 1927. Serial No. 160,860.

This invention relates to means for imparting tension to a yarn or thread in knitting machines and particularly to means for imparting tension or greater tension to one of the two or more yarns which are fed in a plaiting relation in knitting machines.

In order that the principle of the invention may be readily understood I have disclosed a single embodiment thereof in the accompanying drawing, wherein—

Fig. 1 is a side elevation of the latch ring of a circular knitting machine having my invention applied thereto;

Fig. 2 is an inside view in vertical section of the construction shown in Fig. 1; and

Fig. 3 is a plan view of the same.

An important purpose of my invention is the provision of means for applying tension or increased tension to a yarn or thread close to the knitting point or close to the point of engagement of the yarn or thread with the needles in a knitting organization. While the invention may be used in other relations, it is of particular importance when used in plaiting, and I will describe the invention with particular reference to that use without, however, in all the claims limiting it thereto. I will for purposes of description merely disclose the same as used in a circular knitting machine of the latch needle type, although it is to be clearly understood that it may be used in other types of knitting machines particularly of the independent needle type, and that it may be used with either spring beard needles, latch needles, or needles of any other type, as for example sliding latch needles.

Referring to that embodiment of the invention herein shown, I have at 1, in the several figures, indicated a latch ring of a circular knitting machine, it being understood that if the invention is applied to a spring beard needle machine, a partial ring or member adapted to that type of machine will be used instead. Upon said latch ring I mount one or preferably a series of yarn guides or fingers, and for that purpose I have herein represented a series 2 of yarn guides pivoted side by side at 3 in a manner well understood in the art, as, for example, in the Banner knitting machines. I have shown said latch ring 1 as provided with a throat 4 down into which the proper yarn guide or finger is swung when the yarn or yarns pertaining thereto is or are to be

brought into action. The several yarn fingers may be used to introduce yarns or threads as desired, as, for example, in knitting hosiery wherein one yarn will be fed for the cotton or lisle top, a silk yarn for the boot portion of the stocking, a different yarn for the heel and toe, and a reinforcing yarn for the high splice, the heel, the sole of the foot, and the toe.

At 5, I have indicated one of the yarn guides or fingers to which my invention particularly relates. It is particularly adapted to be used in plaiting and for that purpose it is provided with means for supplying two yarns to the needle in a plaiting relation, it being understood that more than two yarns may be fed in a plaiting relation if desired.

In feeding yarns in a plaiting relation, it has heretofore been proposed to impart a greater tension to one of said yarns than to the other, as, for example, to the yarn which is the front or face yarn in normal plaiting, as is disclosed in the patent to Robert H. Lawson, No. 1,605,895, dated November 2, 1926. I have discovered that very beneficial results are secured if the tension is applied to the yarn and particularly if it is applied to one of the plaiting yarns very close to the knitting point or to the point where the yarn issuing from the yarn finger comes in contact with the stems of the needles. So far as I am aware, it has never been proposed to apply tension to one of the plaiting yarns at such point; on the contrary, the increased tension in plaiting has always heretofore been applied at a point more or less remote from the knitting point or from the point where the plaiting yarn comes in contact with the needle stems.

While different constructions may be employed in order to secure the result aimed at by my invention, I preferably provide the following construction to which my invention is not necessarily restricted, and which I will describe as the preferred embodiment.

In the yarn finger 5 I provide a passage 6 for the yarn 7 which is the back yarn in normal plaiting. At some other point or part of the said yarn finger I provide means for feeding the other yarn which preferably is the front or face yarn in normal plaiting. As here shown, I have in advance of and slightly spaced from the yarn passage 6 provided a post, extension or formation 8 extending upward from the body of the finger 110

and provided with a yarn passage 9, the said yarn finger having a yarn passage 10 preferably vertically aligned with the passage 9. The post 8 is cut away or reduced in 5 shape or diameter between the yarn passage 9 and the yarn passage 10, so that the yarn 11, as it is fed from the point of supply, passes first through the passage 9, is then wrapped once or if necessary more than 10 once around a reduced portion of the post, as clearly shown in Fig. 1, and then passes through the eye or passage 10, and thence to the needles, as clearly indicated in Figs. 2 and 3.

15 The fact that the yarn 11 is wrapped one or more times around the post 8 results in increased tension to that yarn, and said tension, being imparted at a point which is very close to the knitting point, is very accurately controlled and is in no wise lost or impaired between the point of application of the tension and the knitting point.

It is not necessary that the yarn finger be of a pivoted type, though this construction 25 is preferred, and the post, extension or formation 8 may be obviously varied in shape without departing from my invention.

Having thus described one embodiment of my invention, it is to be understood that all 30 though specific terms are employed, they are used in a generic and descriptive sense, and not for purposes of limitation, the scope of the invention being set forth in the following claims.

35 I claim—

1. In a knitting machine, a member, such as a latch ring, having a throat therein, a yarn guide or finger movably mounted in said throat and having a formation where- 40 by tension may be imparted to the yarn thereof close to the knitting point.
2. In a knitting machine, a member, such as a latch ring, having a throat therein, a yarn guide or finger movably mounted in 45 said throat and having means for supplying two yarns in a plaiting relation, said finger having means for applying tension to one of said yarns close to the knitting point.
3. In a knitting machine, a member, such

as a latch ring, having a throat therein, a 50 yarn guide or finger for plaiting movably mounted in said throat and having a passage for one of the yarns, said guide or finger having means for applying tension to the other of said yarns. 55

4. In a knitting machine, a yarn guide having an extension around which a yarn or thread can be wrapped to apply tension thereto at a point close to the knitting point.

5. In a knitting machine, a yarn guide or 60 finger having a passage for one yarn and also having an extension around which another yarn may be wrapped to apply tension thereto on its way to the needles.

6. In a knitting machine, a yarn guide or 65 finger having distinct passages for two yarns and an extension around which one of said yarns may be wrapped to impart tension thereto.

7. In a knitting machine, a yarn guide or 70 finger having a post with two spaced yarn passages therein so that yarn or thread can be delivered through the first passage, then wrapped about the post to impart tension to the yarn or thread and then pass through 75 the second passage.

8. In a knitting machine, a latch ring or the like having a series of yarn fingers adapted to be moved into and out of feeding relation, one of said yarn fingers having 80 spaced passages therein for the feeding of two yarns in a plaiting relation, said yarn finger having a post or extension around which one of said yarns may be wrapped to apply tension thereto at substantially the point of delivery of the yarn to the stems of the needles. 85

9. In a knitting machine, a pivoted yarn finger having a delivery end adapted to be presented in close proximity to the needles, said finger having spaced means for delivering two yarns to the needles in a plaiting relation but with one of said yarns tensioned more than the other at a point close to its delivery from said yarn finger. 90

In testimony whereof, I have signed my name to this specification.

JAMES MAIR.
